FIG. 3.

INVENTOR
JOSEPH HOWARD MAYHEW
BY *Paul & Paul*
ATTORNEYS

UNITED STATES PATENT OFFICE.

JOSEPH HOWARD MAYHEW, OF MINNEAPOLIS, MINNESOTA.

APPARATUS FOR HEATING AND TEMPERING GRAIN.

1,361,475.

Specification of Letters Patent.

Patented Dec. 7, 1920.

Application filed August 21, 1916. Serial No. 116,093.

To all whom it may concern:

Be it known that I, JOSEPH HOWARD MAYHEW, a citizen of the United States, and resident of Minneapolis, in the county of Hennepin and State of Minnesota, have invented certain Improvements in Apparatus for Heating and Tempering Grain, of which the following is a specification.

This invention relates to improvements in apparatus for heating and tempering grain and particularly to improvements in the machine described and claimed in Letters Patent of the United States No. 1,181,434, issued May 2nd, 1916, to Clarence W. Carter, of Minneapolis, Minnesota.

The object of the invention is to provide means for controlling the passage of the steam to and from the heating pipes or tubes and thereby increasing or decreasing the number of such pipes that will be in use during the operation of the machine.

The invention consists generally in the constructions and combinations hereinafter described and particularly pointed out in the claims.

In the accompanying drawings forming part of this specification,

Figure 1 is a side elevation of a machine embodying my invention, a portion of the structure being broken away on the line 1—1 of Fig. 2 to show the construction of the header.

Fig. 2 is a vertical section on line 2—2 of Fig. 1 looking in the direction of the arrow *a*.

Fig. 3 is a partial elevation of the section, the section being taken on line 3—3 of Fig. 2, looking in the direction of the arrow *b*.

In the drawings, 2 represents the frame of the machine, 3 the rotatable cylinder, 4 the outer pipes and 5 the inner pipes arranged within said cylinder. All of these parts may be constructed and arranged substantially as shown in the Carter patent hereinbefore referred to. As in the machine made under that patent, the heads of the cylinder are stationary as are also the group of steam pipes, and only the cylinder or incasing shell rotates. The casing or shell rolls upon the rotatable rolls or supports 22, and it is rotated by suitable means, for instance by a toothed wheel on a driven shaft working in a toothed rack encircling and secured to the outside of the cylinder which details are not shown as they are old

in the Carter machine and not claimed herein. The longest pipe 23 of the group of pipes shown is supported at one end by the stationary plate 24 and passes through an inner plate 25 which is sustained from the long pipe, and in turn supports the shorter pipes passing therethrough and also through a second inner plate 26 through which the shortest pipes pass and by which they are supported, substantially as in the Carter machine referred to, and which features are not claimed herein. As stated before all of these pipes are stationary and the outside shell or casing encircles the entire group or bank and is rotatable around them.

Any suitable means, preferably that set forth in the said Carter Patent No. 1,181,434, may be employed for rotating the cylinder 3.

At the end of the machine to which the steam is conducted, I arrange a stationary, hollow header 6. This header is provided with an inner wall 7 in which the ends of the pipes 4 are seated, an outer vertical wall 8, and an intermediate wall 9 in which the ends of the inner or smaller pipes 5 are seated. Upon the outer wall 8 of said header I provide a vertical chamber 10 to which the main steam supply pipe 11 is connected, and I provide a plurality of openings 12 through the wall 8 communicating with the space between said outer wall 8 and the intermediate wall 9. I also provide a plurality of partitions 13 preferably extending horizontally between the walls 8 and 9, and thereby dividing the space between said walls into a plurality of separate compartments or chambers. I have here shown two of these partitions, one arranged a little below the center of the header, and the other a short distance above the center of said header. The arrangement of these partitions is shown clearly in Fig. 2 of the drawings.

I have shown the inlet end of the cylinder broken away at the right hand portion of Fig. 1 of the drawings, and have indicated a suitable inlet spout through which grain may be fed to the interior of the machine.

At the head of the machine or the end opposite that at which the steam is admitted, I provide an inclined spout (not lettered) as shown at the right hand of Fig. 1 through which the grain to be treated is fed to the interior of the revolving cylinder.

This spout corresponds to the feed spout 49 in the Carter patent hereinbefore referred to.

I also provide similar partitions 14 between the intermediate wall 9 and the inner wall 7 of said header. These partitions divide the space in said header into compartments similar to those provided between the walls 8 and 9.

10 I also provide upon the outside of the vertical wall 8 of the header a chamber 15 shown in outline by the dotted lines in Fig. 2 and in section in Fig. 3, and I connect this chamber with the compartments between the walls 8 and 9 by suitable pipes or ducts 16. I also provide this chamber with a suitable drainage pipe or duct 17, located near the bottom thereof.

I also provide within the chamber 10 suitable valves 18 provided with operating hand wheels 19 by means of which the openings 12 between the chamber 10 and the compartment between the walls 8 and 9 of the header may be closed or opened.

25 I also prefer to arrange within the chamber 15 suitable valves 20 having hand wheels 21 by which the openings extending from the compartment between the walls 7 and 9 and the chamber 15 may be closed or opened.

Operation.

With the valves 18 and 20 all open steam admitted through the pipe 11 to the chamber 10 reaches all of the compartments between the walls 8 and 9, and enters all of the inner pipes 5, and traversing said pipes returns to the compartment between the walls 7 and 9, through the larger pipes 4, 40 and the water of condensation passes from these compartments into the chamber 15 and flows out of the waste pipe 17. By closing the upper valve 18 the steam will be shut off from the upper compartment in the header and likewise from the upper tubes of the battery. By closing the other valve 18 the steam is shut off from the intermediate or second compartment of the header.

50 It is also desirable to close the opening leading from the compartments between the walls 7 and 9 and the chamber 15, as otherwise steam that has passed through the pipes would back up and find its way into these compartments. By means of the valves 20 the openings from the inner compartment of the header to the chamber 15 may be closed.

I do not limit myself to any particular form or shape of the chambers 10 and 15, or to any specific number of partitions, or to any particular number of compartments into which said header may be divided by said partition.

The details of the construction may obviously be varied in many particulars without departing from my invention.

I claim as my invention:

1. The combination, in a grain heater, with a rotating cylinder and a battery of radiation pipes arranged therein, of a header arranged at the end of said cylinder, and provided with two series of compartments, means supporting said pipes in communication with said compartments and means for independently controlling the passage of steam to and from said compartments, substantially as described.

2. The combination, in a grain heater, with a rotating cylinder and a battery of radiation pipes arranged therein, of a header provided with two series of compartments, a steam chamber communicating with all of the compartments of one series, means controlling the passage of steam from said chamber to said compartments, and means supporting said pipes in communication with said compartments, substantially as described.

3. The combination, in a grain heater, with a rotating cylinder and a battery of radiation pipes arranged therein, said pipes being provided with two series, one inside of the other, of a header provided with a series of compartments in communication with the inner series of pipes, and another series of compartments in communication with the other series of pipes, and means controlling the passage of steam to and from said compartment, substantially as described.

4. The combination, in a grain heater, with a rotating cylinder and a battery of radiation pipes arranged therein, said pipes being provided in two series, one inside of the other, means supplying steam to one series of pipes and means permitting the escape of steam and any water of condensation from the other series of pipes, and means for cutting off at will passage of steam to any desired number of said pipes, substantially as described.

In witness whereof, I have hereunto set my hand this 16th day of August, 1916.

JOSEPH HOWARD MAYHEW.
